Primary Examiner — Steven J Czyz(74) *Attorney, Agent, or Firm* — Banner & Witcoff, Ltd.(57) **CLAIM**

The ornamental design for a pill dispenser, as shown and described.

DESCRIPTION

FIG. 1 is a front perspective view of a pill dispenser showing my new design;

FIG. 2 is a front top perspective view thereof;

FIG. 3 is a right-side top perspective view thereof;

FIG. 4 is a left-side top perspective view thereof;

FIG. 5 is a top view thereof; and,

FIG. 6 is a front top perspective view of the pill dispenser of FIGS. 1-5 shown with an unclaimed pill bottle environment.

The broken lines depict portions of the article and environment that form no part of the claimed design.
